No. 881,975.

PATENTED MAR. 17, 1908.

W. M. VAN CISE & J. F. CHAMBERS.
CLAMPING AND LOCKING DEVICE.
APPLICATION FILED MAY 8, 1908.

APPLICATION FILED MAY 8, 1906.

UNITED STATES PATENT OFFICE.

WILLIAM M. VAN CISE, OF SUMMIT, NEW JERSEY, AND JONATHAN F. CHAMBERS,
OF WASHINGTON, DISTRICT OF COLUMBIA.

CLAMPING AND LOCKING DEVICE.

No. 881,975.

Specification of Letters Patent. Patented March 17, 1908.

Application filed May 8, 1906. Serial No. 315,746.

To all whom it may concern:

Be it known that we, WILLIAM M. VAN CISE, a resident of Summit, county of Union, State of New Jersey, and JONATHAN F. CHAMBERS, a resident of Washington, District of Columbia, both citizens of the United States of America, have jointly invented new and useful Improvements in Clamping and Locking Devices, of which the following 10 is a specification.

This invention relates to clamping and locking devices and has for its object to provide means by which articles may be clamped and then locked in position. One 15 form of the embodiment of this invention consists in clamping and locking type in position after being assembled so as to permit its removal in the assembled state from place to place.

20 The invention has further for its object to provide means whereby the main-bar of the type-locking device may be held in place while type is being received in the galley from certain kinds of type casting, setting 25 and assembling machines, said main-bar when so held in place serving as a side-guide for the type.

For this purpose the invention consists of 30 a clamping and locking device, comprising a main-bar, auxiliary bars having one end of each of their ends pivotally connected together and one or both of their free ends adjustably movable along the main-bar.

The invention consists further of the combination of a main-bar and a supporting piece movable along the main-bar, the supporting-piece consisting of a movable piece and clamping members, and means for simultaneously clamping the members to the 40 movable piece and the main-bar.

The invention consists further of the combination of a main-bar, a head adapter detachably secured to one end of the main-bar, and a tail adapter detachably secured to the 45 other end; said adapters engaging adjustably movable members in the galley-holding parts of type casting, setting or assembling machines.

50 The invention consists further of certain novel features and combinations of parts to be described hereinafter and finally pointed out in the claims.

In the accompanying drawings, Figure 1 represents a perspective view of our improved type-locking device, as applied to a

galley, the latter being shown in dotted lines, Fig. 2 is a plan view of a galley, type-locking device, and parts of a type-casting, setting or assembling machine, and showing the adapters applied thereto, Fig. 3 is a detail side view of the supporting piece as seen from line 3—3 of Fig. 2, Fig. 4 is a plan view of Fig. 3, Fig. 5 is a section taken on line 5—5 of Fig. 4, Fig. 6 is a bottom view of the head adapter, and Fig. 7 is a side view of the tail adapter.

Similar letters of reference indicate corresponding parts.

Referring to the drawings A represents the main-bar of our type locking device, provided with two sets of oppositely arranged longitudinal grooves, one set, a and a^1 , and a second set, a^2 and a^3 . Two runners B and B^1 are arranged movably along the main-bar and each consists of a member having bent 75 ends B^3 , engaging the second set of grooves a^2 and a^3 . Each runner is also provided with means for securing it in a fixed position along the main-bar. Such means may be, as shown in the drawings, a screw b , which 80 when properly rotated serves to cause the bent ends B^3 of the runner to be pressed tightly against the main-bar.

A third runner E is provided, which is movable along one side of the galley. Auxiliary bars D and D^1 have each one end pivotally connected with pins b^4 of this third or common runner E, and each of their other ends pivotally connected with pins b^3 of the runners B and B^1 . When the main-bar is 90 furthest away from the side of the galley on which the common runner glides, the movable main-bar runners are nearest together; and vice versa, when the main-bar is nearest the side of the galley, the movable main-bar 95 runners are furthest apart. When the main-bar is in proper position, and firmly pressed against the type in order to hold it in position, the fastening means, screws b and b^1 as shown in the drawings, are rotated and 100 hold the runners securely in position, whereby the main-bar is firmly pressed against the type. Instead of having both runners B and B^1 , movable, one runner may be dispensed with and the end of one of the auxiliary bars pivotally connected to the main-bar itself.

In order to hold the type and press it against the upper part of the galley, a movable support or supporting piece G is pro- 110

vided, which consists of two plates G^1 and G^2 , both of which have their ends g and g^1 engaging grooves a and a^1 of the main-bar. The plate G^1 is provided with a downwardly extending guide-piece G^3 which engages the slot G^4 of the extension piece G^5 . The movable support or supporting piece G is moved along the main-bar, until it presses tightly against the type, whereupon the screw H is properly rotated, so as to bring the two plates G^1 and G^2 closer together, whereby the ends g and g^1 engaging the grooves a and a^1 clamp the main-bar A , and hold the support in position thereon, while the plates themselves simultaneously clamp the extension piece G^5 and hold it in position. One end of the extension piece G^5 , is slotted to permit its movement by and past the screw H .

With the main-bar firmly pressed against the type at one side and the supporting piece firmly pressed against the type at one end, the type is securely locked in position in the galley, whereby the galley with the type may be readily moved from place to place. When desired the type may be readily unlocked by the loosening of the fastening means.

In order to use the improved device in connection with a monotype casting machine, the main-bar is provided with holes at its ends, one set a^4 and a^5 , being at one end, and a second set a^6 and a^7 being at the other end. The set a^6 and a^7 are engaged by pins m and m^1 of a head adapter M , consisting of a bent plate, the projecting end m^2 of which engages a slot m^3 of a member m^4 , adjustably movable by a screw m^7 in a slot m^6 of the galley holding part m^5 of a monotype casting machine. The other set of holes a^4 and a^5 are engaged by pins n and n^1 of a tail adapter N consisting of a bar having an additional pin n^2 , which is adapted to engage a hole n^3 of a member n^4 adjustably movable by a screw n^5 in a slot n^6 of the galley holding part n^7 of a monotype casting machine. Before operation, the main-bar is placed in position, the members m^4 and n^4 moved into proper position, the head and tail adapters applied, and then the type cast.

Our improved device is simple in construction and may be readily applied. If, when as shown in the drawings, the device is applied to monotype casting machines, the operation is as follows: The members n^4 and m^4 are moved into proper position so that the main-bar A is in alignment therewith when the adapters M and N are applied. When the type is set, the adapters are removed, and the main-bar A forced tightly against the type, whereupon the fastening screws b and b^1 of the runners are rotated and the runners secured in position. Thereby the main-bar is held tightly against the type. Then the supporting piece G is moved against the type as to press tightly against it, the exten-

sion piece G^5 having been moved as to abut against the galley, whereupon the screw H is rotated and thereby the extension piece clamped and the supporting piece itself secured in position on the main-bar.

We have described one form of our improved clamping and locking device, as specially applicable for type locking and transferring purposes, but we do not wish to limit ourselves to the use of the device described solely for locking type, as the same may be used, for instance, for holding many kinds of material firmly in position. Nor do we wish to limit ourselves to the particular form and construction of the device and adapters illustrated in the drawing, as many changes might be made without departing from the spirit of our invention.

Having thus described our invention, we claim as new and desire to secure by Letters Patent:

1. A clamping and locking device, comprising a main-bar, auxiliary bars having one of each of their ends connected, and runners adjustably movable along the main-bar, pivotally connected with the free ends of the auxiliary bars, substantially as described.

2. A clamping and locking device comprising a main bar, auxiliary bars loosely interconnected at one end, runners attached to the free ends of said auxiliary bars and independently movable along said main bar, and a screw to hold each runner in position.

3. A clamping and locking device, comprising a main-bar, runners adjustably movable along the main-bar, auxiliary bars each having one of their ends pivotally connected with the runners, and a common runner having the free ends of the auxiliary bars pivotally connected thereto, substantially as described.

4. A clamping and locking device, comprising a main-bar having grooves, runners engaging said grooves, means for securing the runners in position, a common runner, and auxiliary bars each having one of their ends pivotally connected with the common runner, and the other ends pivotally connected with the runners movable along the bar.

5. The combination of a main-bar, and a supporting piece, said supporting piece consisting of plates, a movable extension piece between the plates, and means for simultaneously securing the movable extension piece between the plates and the supporting piece in position on the main-bar.

6. The combination, with the galley-holding part and the galley, of a main bar extending across the galley, and means for adjustably connecting the ends of said main bar with said galley-holding part.

7. The combination, with the galley-holding part and the galley supported thereby, of a main bar extending across the galley, and means to secure the ends of said main bar to

said galley-holding part so that said main bar is adjustable transversely of the galley.

8. The combination, with the galley-holding part, of a main bar, and an adjustable sliding connection between the ends of said main bar and said part.

9. The combination, with the galley and a support therefor, of a member guided in said support transversely of the galley, and a clamping and locking device in connection with the galley and embodying a main bar connected at one end with said member.

10. The combination, with the galley and the galley-holding part, of a member guided in said part transversely of the galley, a main bar extending across the galley, and an adjustable connection between said main bar and said member.

11. The combination, with the galley-

holding part and the galley, of devices guided in said part at either end of the galley transversely of the latter, a main bar extending across the galley, and adapters secured to said devices and adjustably connecting the same with said main bar at the ends of the latter.

In testimony, that we claim the foregoing as our invention, we have signed our names in presence of subscribing witnesses.
